United States Patent Office

Des. 232,659
Patented Sept. 3, 1974

232,659

SCALE

Peter M. Cameron, 9 Rosewood Lane,
Owings Mills, Md. 21117

Filed Jan. 26, 1972, Ser. No. 221,136

Term of patent 14 years

Int. Cl. D10—04

U.S. Cl. D52—6 A

FIG. 1 is a top plan view of a scale showing my new design, the bottom plan view being a mirror image thereof; and

FIG. 2 is a left side elevational view, the right side being substantially plain and unornamented.

I claim:

The ornamental design for a scale, as shown and described.
